UNITED STATES PATENT OFFICE

153,739

DESIGN FOR A TABLE OR SIMILAR ARTICLE

Donald A. Wallance, New York, N. Y.

Application April 23, 1948, Serial No. 145,926

Term of patent 7 years

(Cl. D33—14)

To all whom it may concern:

Be it known that I, Donald A. Wallance, a citizen of the United States and residing at New York, in the county of Queens and State of New York, have invented a new, original, and ornamental Design for a Table or Similar Article, of which the following is a specification, reference being had to the accompanying drawings, forming a part thereof.

Figure 1 is a perspective view of the table with the leaves in elevated position;

Figure 2 is a similar view with the leaves in lowered position;

Figure 3 is a side elevational view of the table as shown in Figure 1;

Figure 4 is an end elevational view;

Figure 5 is a bottom plan view;

Figure 6 is a side elevational view of the table with one leaf in lowered position, and

Figure 7 is an end elevational view of the table with the remote leaf in lowered position.

I claim:

The ornamental design for a table or similar article, as shown.

DONALD A. WALLANCE.
